[57] CLAIM

The ornamental design for a combined laptop computer holder and integral wrist rest and pencil case, as shown and described.

DESCRIPTION

FIG. 1 is a left rear perspective view of the claimed invention;

FIG. 2 is a left front perspective view of the claimed invention;

FIG. 3 is a top view of the claimed invention;

FIG. 4 is a left side view of the claimed invention;

FIG. 5 is a front view of the claimed invention;

FIG. 6 is a back view of the claimed invention; and,

FIG. 7 is a bottom view of the claimed invention.

A right side view of the invention, not shown, is a mirror image of the left side view of FIG. 4.
